WO 95/15410
A1 6/1995 WIPO ..... D04H 13/00*Primary Examiner*—Robert M. Spear[57] **CLAIM**

We claim the ornamental design for embossed tissue, as shown and described

DESCRIPTION

FIG. 1 is a top plan view of an embossed tissue showing our new design. The bottom plan view forms no part of the claimed design. The embossed tissue is shown cut away on each of its four sides to indicate indeterminate length and width. The broken lines form no part of the claimed design and depict one repeat unit of the design which repeats uniformly; and,

FIG. 2 is an enlarged fragmentary cross-sectional view along line 2—2 of FIG. 1.
